UNITED STATES PATENT OFFICE

148,810

DESIGN FOR A CORKSCREW

Marshall T. McDowell, Eatentown, N. J., assignor
to The Korkmaster Company, Red Bank, N. J.,
a corporation of New Jersey

Application April 26, 1946, Serial No. 128,997

Term of patent 14 years

(Cl. D44—29)

To all whom it may concern:

Be it known that I, Marshall T. McDowell, a citizen of the United States, residing at Eatentown, county of Monmouth, and State of New Jersey, have invented a new, original, and ornamental Design for a Corkscrew, of which the following is a specification, reference being had to the accompanying drawing, forming a part thereof.

Figure 1 is a side view of a corkscrew embodying my new design showing the corkscrew portion withdrawn.

Figure 2 is a side view of the corkscrew showing the corkscrew portion expanded.

Figure 3 is a front view thereof.

I claim:

The ornamental design for a corkscrew, as shown and described.

MARSHALL T. McDOWELL.
